DESIGN FOR A BOW-TIE ADVERTISING NOVELTY

Olen C. Beavers, San Antonio, Tex.

Application April 20, 1940, Serial No. 91,827

Term of patent 7 years

To all whom it may concern:

Be it known that I, Olen C. Beavers, a citizen of the United States, residing at San Antonio, in the county of Bexar and State of Texas, have invented a new, original, and ornamental Design for a Bow-Tie Advertising Novelty, of which the following is a specification, reference being had to the accompanying drawing, forming part thereof.

I claim:

The ornamental design for a bow-tie advertising novelty, substantially as shown.

OLEN C. BEAVERS.
